William M. Conner
Inventor

James M. Conner

1872. Improved style of printing
of the letters of the alphabet.

Nov. 19, 1872.

UNITED STATES PATENT OFFICE.

JAMES M. CONNER, OF NEW YORK, N. Y.

DESIGN FOR PRINTING-TYPE.

Specification forming part of Design No. 6,266, dated November 19, 1872.

To all whom it may concern:

Be it known that I, JAMES M. CONNER, of the city and county of New York and State of New York, have originated and designed a new Pattern for Printing-Types, which I call "Pantheon Shaded," reference being had to annexed printed impressions thereof. It differs from every other kind of type in style, shape, and proportion.

What I claim as my invention, and desire to secure by Letters Patent, is—

The design or pattern for printing-types herein set forth, with or without the shade or outline.

JAMES M. CONNER.

Witnesses:

JOSEPH H. TOONE,
WILLIAM QUAIL.
